UNITED STATES PATENT OFFICE.

ARMSTEAD CHAUSSIER, OF NEW ORLEANS, LOUISIANA.

WINDMILL.

Application filed May 5, 1926. Serial No. 106,890.

This invention relates to windmill structures and pertains particularly to an improved construction of top structure.

The primary object of this invention is the

5 provision, in a manner as hereinafter set forth, of a windmill superstructure having an improved means for rotatably supporting the sails and vane of the structure.

The invention contemplates the provision 10 of a relatively large flat annular structure supported by wheels which are pivotally mounted at spaced intervals about the periphery thereof and which run upon the top of a platform, forming a part of the windmill top structure. Upon this revolving annular structure a shaft is mounted which carries the sails and diametrically opposite the end of the sail carrying shaft, there extends the wind vane by means of which the 15 moving structure is held in the wind or made to move transversely thereof or to be held stationary at the option of the user. A vertically reciprocating shaft which extends upwardly through the windmill structure projects through the center of the annular revolving structure and has an eccentric connection with the sail carrying shaft, by means of which the rotary motion of the 20 shaft is translated to a vertical reciprocatory movement.

The invention has for another object a windmill super-structure of strong and durable but simple construction, having few moving parts to get out of order or be replaced and comparatively inexpensive to manufacture and set up.

The invention will be best understood from a consideration of the following detailed description taken in connection with the accompanying drawings forming a part of this specification, with the understanding that the invention is not confined to any strict conformity with the showing of the drawings but may be changed and modified so long as such changes and modifications mark no material departure from the salient features of the invention as expressed in the appended claim.

In the drawings:

50 Figure 1 shows the structure embodying this invention and in side elevation, with the ropes controlling the wind vane connected

with the supporting and holding devices therefor.

Figure 2 is a top plan view of the structure.

Figure 3 is a fragmentary elevation of the structure looking from another side.

Figure 4 is a view of the underside of the platform at the top of the windmill frame.

Figure 5 is a sectional view taken transversely of the platform and the revolving structure which rests thereon and,

Figure 6 is a detailed perspective view of one of the arms carried by the revolving structure, which acts as a rope guide for the control of the vane.

Referring now to the drawings in detail wherein like numerals of reference indicate corresponding parts throughout the several views, there are indicated by the numerals 1, a frame having four standards which are in upright slightly convergent relation as shown and which form the supporting beams for the windmill superstructure. Overlying and fixed to the upper ends of the beams or standards 1, by means of the securing brackets 2, is the platform 3, the same here being shown as of circular design and having a central aperture 4 therethrough. It is of course understood that this platform may be square or octagonal as desired as applicant does not wish to limit himself to a platform of this particular contour. Extending transversely of the underside of the platform 3 is a beam 5, the ends of which abut the inner faces of two of the supporting beams 1 as shown in Figure 3.

The central portion of this beam 5 has a bearing 6 extending therethrough, which bearing has a plate 7 connected to one end thereof which plate is secured to the underside of the beam 5 as shown in Figure 4. The foregoing described structure forms the permanently stationary portion of the windmill structure.

The movable portion of the superstructure comprises an annular member 8 having the central aperture 9 therethrough and this member is positioned in superposed relation to the platform 3.

A plurality of brace arms 10 are arranged over the moving structure 8, the lower end of each arm being angled to provide a foot

11 which is secured by means of the bolts 12 to the moving member. The upper ends of these arms converge to and merge with a central plate 13 which is arranged directly over the bearing 6 and has an aperture therethrough in alignment with the said bearing. The arms 10 as shown, thus set up a pyramid shaped structure over the central opening or well 9 of the rotatable member 8.

10 The ends of the foot portions 11, are extended outwardly beyond the periphery of the member 8 and turned downwardly extending a substantial distance below the underface thereof as shown in Figures 1 and 5. 15 These downturned portions 13' of the foot members 11 each has secured thereto by means of the stub shaft 14, the supporting wheel 15. As is clearly shown in Figures 1 and 5, these supporting wheels run upon the top of the platform 3 and support the structure 8 and adjacent elements, over the platform.

Extending upwardly through the windmill structure and through the bearing 6 and 25 the plate 13, is a vertically reciprocable pump operating rod 16. The upper portion of this rod 16 directly beneath the plate 13, has a collar 17 secured thereabout from which a connector 18 extends.

30 Mounted upon the revolvable member 8 is a pair of aligned bearings 19 and extending through these bearings, radially of the member 8, is a shaft 20 upon the outer end of which a sail wheel, indicated generally by the numeral 21, is mounted. The inner end of the shaft 20 extends to a point adjacent to the shaft 16 and is operatively connected through the medium of the part 22 and connector 18, so that on revolution of the shaft 40 20 the pump rod 16 will be operated. The part 22 and connector 18 construction here shown may be of any appropriate design suitable for the use herein described.

Mounted upon the revolvable member 8, in 45 alignment with the shaft 20 is a vane arm 23, the outer end of which extends a substantial distance beyond the periphery of the member 8 and is reduced as indicated at 24 and is also provided with an aperture.

50 Pivotedly connected to the reduced portion 24 of the vane arm 23, is the inner end 25 of a vane 26, the portion 25 of the vane being bifurcated to receive the reduced portion 24 of the fixed arm 23. A pivot pin 27 is passed 55 through the furcations of the portion 25 of the vane and through the reduced portion 24, to pivotally secure the same together.

As shown, the fixed arm 23 is arranged directly between two of the foot portions 11 of the supporting arms 10 and extending outwardly from those foot portions 11 which are arranged one on either side of the arm 23, is a fixed arm 28. These arms as shown, are parallel with the fixed arm 23 of the vane and have their inner ends secured to the

member 8 by means of the bolts 12 which pass through the adjacent foot portions 11, which bolts extend through the turned ends 29 of the arm. The outer portion of each of the arms 28 extends inwardly at right angles 70 as indicated at 30, toward the vane arm 23 and there is then formed a loop 31 at the inner ends of these inturned portions which loops merge into downwardly extending drop portions 32 which terminate at their 75 lower ends in the double hook 33. The two structures covered by the reference numerals 29 to 33, constitute vane controlling rope supporting and holding elements.

Upon each side of the vane body 26 there 80 is secured an eye 34 and from each of these eyes there extends a control rope 35 which passes through the adjacent loop 31 of the structure above described. These ropes are then extended downwardly and passed 85 through the double hook structure 33 which due to the manner in which the rope is threaded therethrough, forms a frictional resistance to the easy slipping of the rope to maintain the same fast at adjustment thereof 90 to set and regulate the position of the wind vane. As is shown in Figure 1 the depending or drop portions 32 of the rope holding structures extend a substantial distance downwardly in parallel relation and the 95 ends of the rope are trained about the hooks 33 and secured at adjacent points to the same. It will be readily understood that when the vane 26 is held in the manner shown in Figure 1, by means of the control ropes 35, that the sail wheel will be held in the wind and the windmill will operate. In order to throw the sails out of the wind, the ropes 35 are continued from the hooks 33 to the securing eyes 36 and one or the other 100 thereof pulled to swing the vane in the desired direction whereupon the ropes may again be secured to the eyes 36 to hold the vane in the set position in which set position the sails 21 may be partly or completely out 105 of the wind to reduce or stop the operation of the mill and prevent the superstructure from rotation upon the support, as is clearly shown in Figure 3 of the drawing.

From the foregoing description it will be 110 readily seen that an improved windmill super structure has been set up which will be light and easy to operate, yet strong and durable and efficient in action.

Having thus described my invention what 115 I claim is:—

In a windmill structure of the character described, an upright supporting structure having a platform at its top, a power mechanism including a turn table, a spider mounted upon said turn table and having downturned ears depending below said table, journals on said ears, rollers on the journals and adapted to travel upon the platform, means centrally pivoting the spider to 125 130

the platform, a vane support carried by the turn table, a wind vane having vertical pivotal connection with the support, a wind wheel mounted upon said turn table for-
wardly of the vane support, rope guides carried by the turn table on opposite sides of the vane support and each having a double hook terminal and a guide eye above the same, and ropes connected to the wind vane at opposite sides thereof and trained 10 through the eyes of said guides and adjustably and detachably fastened in the double hook terminals of such eyes.

In testimony whereof, I affix my signature hereto.

ARMSTEAD CHAUSSIER.
